UNITED STATES PATENT OFFICE.

EDWARD L. FARR, OF WENONAH, NEW JERSEY.

APPARATUS FOR APPLYING BUSHINGS TO PRINTING-BLOCKS.

SPECIFICATION forming part of Letters Patent No. 632,783, dated September 12, 1899.

Application filed April 8, 1899. Serial No. 712,226. (No model.)

To all whom it may concern:

Be it known that I, EDWARD L. FARR, of Wenonah, Gloucester county, New Jersey, have invented an Improvement in Apparatus for Applying Bushings to Printing-Blocks, of which the following is a specification.

My invention has reference to apparatus for applying bushings to printing-blocks; and it consists of certain improvements, all of which are set forth in the following specification and shown in the accompanying drawings, which form a part thereof.

The object of my invention is to apply bushings to the back of large printing-blocks, such as employed in the printing of oil-cloth, &c., the construction of which printing-blocks and the method of clamping in the machines is shown in the application Serial No. 712,225, filed April 8, 1899.

As the clamping-screw which passes through the form-bed must enter the bushings absolutely true to avoid binding or injury to the threads, it is essential that the bushings shall be accurately placed in the back of the printing-block, so that the axes of the screw-threaded holes shall be exactly at right angles to the back of the block. As the bushings are formed on the exterior with coarse screw-threads and with which they are screwed into suitable holes previously prepared in the back of the block, it is essential that their entry into the wood shall be at right angles to the surface thereof. Otherwise it would be impossible to quickly and accurately clamp the blocks in the press and avoid objectionable

wear and injury to the clamping-screws. In carrying out my invention I first mark upon the back of the printing-block (which contains several square feet of surface) the exact locations where the holes are to come, so that the blocks shall have the holes similarly disposed, and thereby be made interchangeable. After so marking the blocks the same are placed upon a pad with the printing or engraved surface resting thereon, and said pad, with its block, is then arranged upon a boring-machine and the holes accurately bored at right angles to the back surface of the block. The block in this condition is then ready for

the reception of the metallic bushings. The body of these bushings or the diameter at the roots of the external threads is preferably of

the exact diameter of the holes. A guide-plate consisting of a large flat surface adapted to rest upon the back of the block and having an aperture therein exactly at right angles to the under surface of said guide-plate is then laid on the back of the block and over the hole in which the bushings are to be placed. A bushing is then inserted into the guide-plate, and the outer circumference of its outer threads exactly fits the aperture in said guide-plate, and consequently said plate holds the bushings temporarily at exactly right angles to the back surface of the printing-block. A suitable ratchet screw-driver or wrench is then applied to the bushing, and at the same time the latter is forced toward the hole in the wood. Under these combined actions it enters the wood in exactly the right position and permits the operation to be quickly and accurately accomplished without the least danger or injury to the wood. In this manner all of the bushings over the back of the block are speedily and accurately located in position and the central screw-threaded apertures for the clamping-screws from the form-bed will all have their axes arranged absolutely parallel. In printing-blocks of this character it is most important and, in fact, essential to good work that the greatest accuracy in the location and position of these bushings within the block shall be secured, and the present method has been developed after considerable experience and experiment and fulfills all the requirements for perfect work.

My improvements will be better understood by reference to the accompanying drawings, in which—

Figure 1 is a side elevation of apparatus for inserting the bushings in the back of the printing-block and shows the latter in section. Fig. 2 is an enlarged sectional view of a portion of the block, the bushing, and the guide. Fig. 3 is a plan view of the bushing. Fig. 4 is a perspective view of the guide, and Figs. 5 and 6 are plan views of the modified forms of the bushing.

II is a table upon which a flat pad G is adapted to be supported and shifted.

A is the printing-block inverted, with the engraved or printing surface B resting upon the pad G. This printing-block is of large

area, covering several square feet, and being comparatively thin it requires to be clamped at numerous places over its back to the form-bed of the press. This is accomplished by 5 inserting in the wood of the back of block metallic bushings D. The back of the block at predetermined places is accurately bored with holes C at right angles to the back surface, and said holes are of the diameter of the 10 body portion of the bushing H—that is to say, the diameter of the hole C is approximately equal to the diameter of the bushing at the roots of the outer teeth P—so that the teeth shall find a strong hold upon the wood exterior of said hole, but without any tendency 15 to split the wood by forcing a solid body of greater diameter than the hole into it.

The bushing, as set out in my application hereinbefore referred to, has a central screw-threaded aperture O of small diameter, into 20 which the clamping-screws from the form-bed pass, and also is provided with a notch d at the top, into which to place the screw-driver bit for screwing the bushing into the hole.

25 F is a guide-plate made flat upon its bottom, so as to rest upon the block A. It is made of extended area, so as to prevent any uneven support, and is also of such weight that it will retain its position unless positively moved under considerable exertion. This 30 guide-plate F has an upwardly-extending hub E, provided with an aperture e at exactly right angles to the under surface, so that the bushing D in being guided through said aperture is held at exactly right angles to the back of 35 the printing-block and in alinement with the hole C therein. The diameter of the hole e of the guide-plate is such as to just receive the bushing and enable the outer edges of the 40 teeth P thereof to be guided therein, as indicated in Fig. 2. In this manner, no matter how irregular the lower surface of the bushing may be due to the termination of the screw-threads, the bushing is forced to enter the 45 wood in exactly the proper manner to insure its being located therein with the axes of the small screw-threaded aperture O at exactly right angles to the back surface of the block.

When the parts are in the relative positions 50 shown in Figs. 1 and 2, a ratchet screw-driver M, having the bit m, is then placed in position upon the bushing, and downward pressure is applied by a shaft I, which is depressed by means of the lever L, link K, and treadle 55 J. While this pressure is applied, the ratchet screw-driver M is operated by hand and the bushing forced into the wood while being guided by the guide-plate E.

I would point out that by having the guide- 60 plate E loose upon the back of the wood block it automatically adjusts itself over the hole C as the bushing enters the same; but in the entire operation the said guide-plate insures the bushing traveling at exactly right angles 65 to the back of the printing-block and in direct alinement with the holes therein.

The bit m, no matter what its construction

may be, is of smaller diameter than the hole e in the guide-plate F, so that said bit may follow up the bushing as the same is forced 70 through the guide-plate and into the wooden printing-block. It will be seen that the guide-plate continues to act as a guide for the bushing until the bushing is well into the block.

It is self-evident that in place of making 75 the aperture e of a smooth bore its internal surface may be screw-threaded to correspond to the screw-threads P of the bushing. This, however, is undesirable, because if the bushing did not at once enter the wood of the 80 printing-block it might raise the guide-plate from the surface thereof unless positively held down. Under the circumstances, therefore, I prefer that the hole e shall be smooth-bored.

85 By this apparatus and process great rapidity and accuracy is secured in applying the bushings; but it is self-evident that the pressure and power for screwing the bushings into the wood may be accomplished in any suitable 90 manner, even by the use of an ordinary large screw-driver. In the case of Fig. 5 the screw-driver would have a square end to fit into the socket d', while in the case of Fig. 6 the screw-driver or wrench would have a square socket 95 to fit over the square projection d² of the bushing.

Having now described my invention, what I claim as new, and desire to secure by Letters Patent, is—

100 1. Means for applying metallic bushings to a wooden printing-block having an aperture 105 extending at right angles from the back surface, consisting of the combination of a loosely-supported guide-plate having a flat under surface adapted to rest upon the flat back of the printing-block about the hole therein and also having an aperture at right angles to said flat under surface and of greater diameter than the aperture in the wood, and of substantially the same diameter as the threaded exterior of the bushing to be inserted in said aperture.

110 2. Means for applying metallic bushings to a wooden printing-block having an aperture 115 extending at right angles from the back surface, consisting of the combination of a loosely-supported guide-plate having a flat under surface adapted to rest upon the flat back of the printing-block about the hole therein and also having an aperture at right angles to said flat under surface and of greater diameter than the aperture in the wood, and of substantially the same diameter as the threaded exterior of the bushing to be inserted in said 120 aperture whereby said bushing is guided before and during its passage from the guide-plate into the hole of the wooden printing-block and is caused to enter the block in a line at right angles to its back surface, a support or table for the printing-block, a pressure device for applying a downward pressure upon the bushing in a direction toward the wooden block, and a device for rotating the 125 130

bushing while subjected to the downward pressure and guided in the guide-plate.

- 5 3. Means for applying metallic bushings to a wooden printing-block having an aperture extending at right angles from the back surface, consisting of the combination of a loosely-supported guide-plate having a flat under surface adapted to rest upon the flat back of the printing-block about the hole therein and 10 also having an aperture at right angles to said flat under surface and of greater diameter than the aperture in the wood, and of substantially the same diameter as the threaded exterior of the bushing to be inserted in said 15 aperture whereby said bushing is guided before and during its passage from the guide-plate into the hole of the wooden printing-block and is caused to enter the block in a line at right angles to its back surface, a support or table for the printing-block, a pressure device for applying a downward pressure upon the bushing in a direction toward the wooden block, a device for rotating the bushing while subjected to the downward pressure 20 and guided in the guide-plate, and a pad of uniform thickness adapted to receive the engraved or printed surface of the printing-block and movable over the surface of the table or support.
- 25 4. Means for applying metallic bushings to

a wooden printing-block having an aperture extending at right angles from the back surface, consisting of the combination of a loosely-supported guide-plate having a flat under surface adapted to rest upon the flat back of the printing-block about the hole therein and 35 also having an aperture at right angles to said flat under surface and of greater diameter than the aperture in the wood, and of substantially the same diameter as the threaded exterior of the bushing to be inserted in said aperture whereby said bushing is guided before and during its passage from the guide-plate into the hole of the wooden printing-block and is caused to enter the block in a 40 line at right angles to its back surface and a device for rotating the bushing while subjected to the downward pressure the said device consisting of a rotating spindle or shank having an irregular surface adapted to fit the 45 configuration of the upper surface of the bushing and of a diameter less than the diameter of the hole in the guide-plate.

In testimony of which invention I have hereunto set my hand.
